BY *John A. Cooney*

ATTORNEY

UNITED STATES PATENT OFFICE

JOHN A. COONEY, OF TULSA, OKLAHOMA, ASSIGNOR OF ONE-FOURTH TO HARRY F. QUINLAN, OF TULSA, OKLAHOMA

ROTARY BIT

Application filed April 29, 1929. Serial No. 359,023.

My invention relates to drilling bits and more particularly to devices of that character for use in drilling oil wells; the principal object of the invention being to increase the usefulness and to reduce the cost of maintenance of bits of this type, by providing removable cutters in the body portion of the tool, so that the cutters may be removed for sharpening, tempering and for replacement by cutters of different materials to suit the nature of the formations being drilled.

In accomplishing these and other objects of the invention I have provided improved details of structure, the preferred forms of which are illustrated in the accompanying drawings, wherein:

Fig. 1 is a perspective view of my improved drilling bit.

Fig. 2 is a central longitudinal section 20 through the bit.

Fig. 3 is a detail perspective view of the head of the bit stem.

Fig. 4 is a transverse section on the line 4-4, Fig. 3.

25 Referring in detail to the drawings:

1 designates the assembled drilling bit including a core member 2 comprising a stem 3 having a threaded upper end 4 and provided with a conical-shaped head 5 at its lower end 30 and with an opening 6 extending centrally and longitudinally through the stem and head portion.

The head portion 5 of the core member includes oppositely tapered conical surfaces 7 35 and 8, the lower surface 7 having annular portions 9, 10 and 11 of equal width and inset from each other to form shoulders 12 and 13, the lower portion being provided with a flat bottom surface 14.

40 The upper conical surface 8 converges with the stem 3, and extending radially outward from the stem 3 are a plurality of equally spaced slits 15 dividing the head into segments 16.

45 Provided in the segments 16 are openings 17, 18 and 19 extending angularly downward from a substantially central position on the conical surface 8, the openings 17 extending through the slits 15 and shoulder 13, the openings 18 having a less angle of inclination and

extending through the slits and centrally through the annular portion 9 of the surface 7. The openings 19 are located centrally between the slits and extend downward at a greater angle of inclination than the openings 17 and open through the shoulder 13.

55 Mounted in the openings 17, 18 and 19 are cutters 20 comprising cylindrical bodies 21 projecting from the head 5 and having tapered outer ends 22 forming cutting edges 23, and having transverse slots 24 at their opposite ends for engagement by a retainer ring 25.

60 The retainer ring 25 extends around the conical surface 8 and is anchored to the head 5 by an anchor stud 26 and by an inturned end 27 of the ring engaging an aperture 28 in the head.

65 Located in the upper surface of the segments 16 and centrally between the slits 15 are recesses 29 extending radially outward from points in diametrical alignment with the upper ends of the openings 17, 18 and 19. Mounted in the recesses 29 are cutters 30 similar to the cutters 20, and having transverse slots 31 at their upper ends engaged by the retainer ring 25.

70 Located at the upper end of the slits 15 in the head 5 are a plurality of openings 32 equally spaced around the stem 3 and extending downwardly at varying angles through the flat bottom surface 14.

75 Mounted in the openings 32 are cutters 33 similar to the cutters 20 except for length, the lower ends of the cutters projecting angularly from the bottom face 14 of the head, and the upper ends thereof having transverse slots 34 engaged by a retainer ring 35 which encircles the stem 3.

80 Assembled on the stem 3 above the head 6 is a sleeve 36 having an enlarged lower end 37 slightly larger in diameter than the head 5, and central opening 38 snugly engaging the stem and provided with a tapered counterbore 39 fitting the surface 8 of the head.

85 Recesses 40 are provided in the tapered surface of the counterbore and align with the openings 17, 18 and 19, and with the recesses 29 in the head 5 for receiving the portions of 100

the cutters protruding from the upper conical surface 8.

The upper end of the sleeve 36 is provided with an enlarged portion 41 having a tapered end surface 42 and a ring portion 43 projecting upwardly from the upper end of the tapered surface for engagement by a retainer collar 44.

Formed in the tapered surface 42 and extending radially outward from the ring portion 43 are a plurality of equally spaced grooves 45 fitted with cutters 46 similar to the cutters 20 and having slots 47 at their upper ends engaged by a retainer ring 48 extended around the ring portion 43.

The retainer collar 44 includes a body portion 49 equal in diameter to the enlarged portion 37 of the sleeve 36 and provided at its upper end with a reduced neck 50. An opening 51 extending centrally through the collar is provided with tapered counterbores 52 and 53 at its opposite ends and the lower portion of the opening is engaged by the ring portion 43 on the sleeve member.

A threaded opening 54 is provided in the side wall of the collar and fitted with a set screw 55 engageable with the stem 3 for retaining the sleeve member on the stem during the assembly of the device.

Recesses 56 are provided in the tapered surface of the counterbore 52 and register with the grooves 45 in the sleeve 36 for receiving the protruding portions of the cutters 46.

Mounted on the stem 3 above the collar 44 is a coupling member 57 having a threaded opening 58 engaging the threaded portion 4 of the stem and provided with a tapered lower end 59 fitting the counter bore 53 and adapted for urging the head 5, sleeve 36 and collar 46 into assembled relation.

Formed at the upper end of the coupling member 57 is a shank 60 provided with a central opening 61 communicating with the opening 6 in the stem 3, and formed on the shank are threads 62 for attachment to drill pipe 63 whereby the bit is operably connected with actuating means when in operation.

When the device is assembled the cutters are secured by the retainer rings 25, 35 and 48, and by the clamping action of the sleeve 36 and retainer collar 44.

When it becomes necessary to remove the cutters for sharpening, tempering or replacement, the coupling member 57 is removed from the stem 3, and the set screw 55 is disengaged from the stem to permit removal of the collar 44 and sleeve 36.

With the sleeve removed from engagement with the head and the collar 44 removed from engagement with the sleeve 36, the retainer rings and head portions of the cutters are exposed so that the cutters may be removed and replaced as desired.

What I claim and desire to secure by Letters Patent is:

1. A drill bit including a stem having a through central opening, a head at one end of the stem, a threaded portion at the opposite end of the stem, cutter members on the head, a retainer ring on the head and engaging said cutters, a sleeve member on the stem engaging said cutters, reaming cutters on the upper end of said sleeve, a retainer ring on the sleeve engaging said reaming cutters, a collar member on the stem engaging said reaming cutters, and a coupling member on the threaded portion of the stem, having a through channel communicating with the opening in the stem.

2. A drill bit including a stem having a through channel, a conical-shaped head at one end of the stem having radially disposed openings, a threaded portion at the opposite end of the stem, cutter members in the head openings having portions protruding from said head and provided with transverse slots, a retainer ring on the head engaged in said slots, a sleeve member on the stem engaging the head and the protruding portions of said cutters, said sleeve having radially disposed grooves at its upper end, reaming cutters in said grooves having portions protruding from the sleeve and provided with transverse slots, a retainer ring on the sleeve engaged in said slots, and a coupling member on the threaded portion of the sleeve engaging the protruding portions of said reaming cutters, having a through opening communicating with the channel in said stem.

3. In a drill bit, a stem including a conical head having openings extending through its side and top faces, cutter members removably located in said openings with their ends extended from the side and top faces of the head, a retaining ring engaging the upper ends of the cutter members, and a sleeve on the stem, engaging the head and recessed to seat the upper ends of the cutter members.

4. In a drill bit, a stem including a conical head having a bevelled top face and having openings extended through its side and top faces, cutter members in said openings having cutting ends extended from the side face and grooved ends extending from the top face, a ring seated in the grooves in the upper ends of the cutter members, a sleeve on the stem seated on the upper face of said head and recessed to seat the upper ends of the cutter members, and means for retaining the sleeve on the stem.

5. In a drill bit, a stem including a conical head divided longitudinally and having mating grooves in the side faces of its segments extending through the side and top faces of the head to form openings, and having radial grooves in the upper faces of its segments, cutter members in said openings projecting from said side and top faces, cutter members

in said grooves having cutting ends projecting from the side of the head, a retaining ring engaging the upper ends of said cutter members, a sleeve in the stem recessed to seat the 5 projecting upper ends of the first named cutter members, and having radial grooves cooperating with the radial grooves in the head to seat the second named cutter members, and means for retaining the sleeve on the stem.

10 In testimony whereof I affix my signature.
JOHN A. COONEY.
